V. FLOCKER,
HANGING STRAP FOR STREET RAILWAY CARS.
APPLICATION FILED SEPT. 15, 1915.

1,182,467.

Patented May 9, 1916.

UNITED STATES PATENT OFFICE.

VINCENT FLOCKER, OF PITTSBURGH, PENNSYLVANIA.

HANGING STRAP FOR STREET-RAILWAY CARS.

1,182,467.

Specification of Letters Patent.

Patented May 9, 1916.

Application filed September 15, 1915. Serial No. 50,826.

To all whom it may concern:

Be it known that I, VINCENT FLOCKER, a citizen of the United States, and resident of Pittsburgh, county of Allegheny, State 5 of Pennsylvania, have invented certain new and useful Improvements in Sanitary Removable Hanging Straps for Street-Railway Cars, of which the following is a specification.

10 This invention relates to hanger straps provided in street cars for the benefit of standing passengers and the object of this invention is to provide a hygienic hand strap which can be quickly and easily detached from its supporting rod, cleaned, and replaced.

Many car straps are now provided with a coating or cover of celluloid which is sanitary and prevents to a great degree the possibility of transferring disease germs from hand to hand, which possibility is ever present when the leather of the strap itself is exposed to be grasped by dirty and perspiring hands. Straps having this protective covering of celluloid or other non-absorbent material are sanitary not only because they are not so readily infected as leather but also because the protective covering is adapted to be cleaned and disinfected. In cleaning and disinfecting the straps it is highly desirable that the straps may be taken down from the high rod on which they are supported and dipped or washed, as to wash and disinfect each individual strap while it hangs in the car obviously would require much time, and the disinfection is not so surely accomplished.

Various methods of fastening hanger straps to their supporting rods have been 40 used heretofore, such as providing them with buckles, rivets and screw-rivets, but these are in the nature of permanent fastenings and none of these fastening devices allows the hanger strap to be quickly attached and detached.

My improved hanger strap is quickly detachable and may be taken down and washed or disinfected and replaced on the supporting rod in a moment, whereby they 50 may be maintained in a sanitary condition without materially delaying the car.

My invention in a simple form is shown in the accompanying drawings, in which:—

Figure 1 is a sectional view of a supporting rod and strap having my improved fastening means attached thereto. Fig. 2

is a side elevation of the same. Fig. 3 is a perspective view of a detail. Fig. 4 is an enlarged longitudinal section of part of my fastening device. Fig. 5 is a top view of 60 the turn button having the handle omitted.

In Figs. 1 and 2 the rod 10 is the usual iron or wood rod rigidly attached to an ear at or near the top. The strap 11 is preferably of leather although woven belting or 65 similar material may be employed, and is arranged in two loops, a small upper loop 12 which encircles the rod, and a large lower loop 13 which serves as a grip for the hand. In the drawings I have shown both 70 loops formed by a single continuous strip of leather and this is the preferable way of making the hanger strap. The lower loop 13 is at all times closed as its ends are securely fastened together by rivets 14. The 75 upper loop 12 is held closed or is opened as desired, its ends not being united by rivets but held together by a separable fastener A, which allows the loop to be opened quickly, and without special tools when desired yet 80 holds it securely closed at other times. The separable fastener A, consists essentially of a turn button mounted on one end of the loop 12 and a slotted plate or guard mounted on the other end, the button being adapted to pass through the slot and to be turned to engage the plate.

The turn button and its supporting mechanism comprises a metal or hard rubber handle 15 having depressions 16 in the sides 90 thereof to form grips for the fingers, a member 17 having a hollow cylindrical recess 18 therein, a cylindrical stem 19 adapted to operate within the recess 18 in the member 17, the members 17 and 19 forming a 95 telescopic swivel joint, and a coil spring 20 held in an annular recess between the stem 19 and the member 17, and adapted to normally press against said members to hold them together. The inner end of the stem 100 19 is provided with an outwardly turned annular flange 23 the diameter of this flange being approximately equal to the diameter of the recess 18 in the member 17. The member 17 has an inwardly turned annular flange 24 on one end, the other end being closed. The diameter of the opening in the 105 end of member 17 within the flange 24 is approximately equal to the diameter of the stem 19 and the member 17 is movable longitudinally of member 19 but cannot be disengaged therefrom because of the flanges 23

and 24 which abut against and are unable to pass each other. It is necessary in constructing the joint in this manner that the member 17 be made in two parts 17^a and 17^b. After being fitted together around the stem 19 the parts 17^a and 17^b are fastened together by screws 17^c and the whole acts as one piece and will be referred to hereafter as such.

10 The coiled compression spring 20 is placed in the annular recess between members 17 and 19 and is adapted to press against the flanges 23 and 24 at all times, the result of which is to hold the members 17 and 19 pressed together. On the other end of loop 12 is fastened by means of rivets 25 a metal casing or guard 26. This guard is raised from the strap a considerable distance by flanges 27, at right angles to the 20 plate. The plate or guard has cut in its center an elongated slot 28, and has at right angles to this slot a groove or depression 29, the slot being large enough to permit the passage of the turn button and the groove being of such shape and dimensions as to receive and engage the turn button. In closing the loop 12 the metal guard is pushed over the handle of the turn button, the latter is drawn outwardly by the fingers against 25 the pressure of the spring until it clears the guard and can be turned to engage the notch. When in the notch the handle cannot be turned, the only way of releasing the button being to pull the button forward against 30 the spring pressure and turn it into position 35

to go through the slot. In other words the spring holds the button normally within the slot or the groove and it can only be turned after pulling it from the slot or groove against the pressure of the spring. 40 This fastener permits the hanger strap to be attached and detached in a minimum of time which is very desirable and is strong and efficient, capable of supporting considerable weight. The lower loop 13 of the 45 strap is provided with a celluloid casing or cover 30 which preferably has small metal collars 31 mounted on the ends thereof to prevent liquids running down along the strap under the cover and which also provide an ornamental finish.

When my improved hanger strap is used, all of the straps in a car may be removed, cleaned and returned in a shorter time than can be done with straps heretofore in use. 55

Having thus described my invention what I claim is:

In a street car hanger strap the combination with a supporting rod of a strap having a grip portion and a loop surrounding 60 the rod, and means for detachably securing the free end of the loop whereby the strap may be quickly removed for cleansing and replaced, said means comprising a turn button and a guard having a slot therein, said 65 turn button being secured by a spring in locked position and rotatable therefrom to free the loop.

In testimony whereof I affix my signature.
VINCENT FLOCKER.
